(57) **CLAIM**

The ornamental design for a smokeless tobacco container holder, substantially as shown and described.

DESCRIPTION

FIG. 1 is a front and left side perspective view of a smokeless tobacco container holder showing my new design;

FIG. 2 is a front elevation thereof.

FIG. 3 is a rear elevation thereof.

FIG. 4 is a top view thereof.

FIG. 5 is a bottom view thereof.

FIG. 6 is a right side elevation thereof, the left side being a mirror image of the right side; and,

FIG. 7 is a rear and right side perspective view thereof.

Environment is indicated by “dash-double-dot” lines, whereas in FIGS. 3 and 7, the dashed lines indicate stitching which forms part of the claimed design.

In all Figures, shading accords to the lighting convention described in 37 C.F.R. § 1.84 (m).

The broken line showing of environment in the drawings is included for the purpose of illustrating only and forms no part of the claimed design.
